US00D846582S

(12) **United States Design Patent** (10) Patent No.: **US D846,582 S**
(45) Date of Patent: **** Apr. 23, 2019**

- (54) **DISPLAY SCREEN OR PORTION THEREOF WITH A GRAPHICAL USER INTERFACE**
- (71) Applicant: **JPMorgan Chase Bank, N.A.**, New York, NY (US)
- (72) Inventors: **Amanda Valladares**, Brooklyn, NY (US); **Amanda Smith**, Brooklyn, NY (US); **Melora Zaner**, New York, NY (US); **Matthew Gromada**, New York, NY (US); **Jay E. Parsons**, Columbus, OH (US); **Jonathan Beck**, New York, NY (US); **Erika Scott**, Brooklyn, NY (US); **Claudio Esposito**, New York, NY (US); **Indeevara H. De Silva**, Lewis Center, OH (US); **Melissa Feldsher**, New York, NY (US); **Geoffrey L. Goetz**, Hilliard, OH (US); **Michael Thornton**, Westerville, OH (US); **Kimberly Chan**, New York, NY (US)
- (73) Assignee: **JPMorgan Chase Bank, N.A.**, New York, NY (US)
- (**) Term: **15 Years**
- (21) Appl. No.: **29/613,547**
- (22) Filed: **Aug. 10, 2017**
- (51) LOC (11) Cl. **14-04**
- (52) U.S. Cl. **D14/486**

Primary Examiner — Jack Reickel*Assistant Examiner* — John M Otte*(74) Attorney, Agent, or Firm* — Hunton Andrews Kurth LLP**CLAIM**

The ornamental design for a display screen or portion thereof with a graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE depicts a front view of a display screen or portion thereof with a graphical user interface showing our design.

The broken lines showing a display screen with graphical user interface is included for the purpose of showing portions of the article which form no part of the claim.
